UNITED STATES PATENT OFFICE.

CLARENCE H. DOCKHAM, OF CLEVELAND, OHIO, ASSIGNOR TO CHICAGO PNEUMATIC
TOOL COMPANY, OF NEW YORK, N. Y., A CORPORATION OF NEW JERSEY.

DRILL.

1,420,417.

Specification of Letters Patent. Patented June 20, 1922.

Application filed October 9, 1920. Serial No. 415,868.

To all whom it may concern:

Be it known that I, CLARENCE H. DOCKHAM, a citizen of the United States, residing at Cleveland, in the county of Cuyahoga and State of Ohio, have invented certain new and useful Improvements in Drills, of which the following is a specification.

My invention relates to drills of the type frequently referred to as rock drills, and 10 the object thereof is to provide a novel and efficient mounting for the drill proper. Heretofore the mounting of the drill has consisted of a rigid shell having guideways on which the machine is adapted to slide, 15 but owing to its rigidity this mounting is subject to injury and breakage from the strains and stresses resulting from the operation of the drill. Moreover, this shell provides an insufficient bearing for the drill 20 structure and also requires frequent adjustment.

My present mounting overcomes these objections and provides a supporting structure which provides elasticity and yet sufficient rigidity for all practical working 25 purposes, and also provides ample bearing for the drill and avoids necessity of adjustment of any guideways. In my construction I also provide for an adjustable 30 cone in connection with said mounting.

In the drawings Fig. 1 is a side elevation of a drilling machine embodying my invention; Fig. 2 a plan view thereof showing the drill proper removed; Fig. 3 a section on the line 3-3 of Fig. 1 but on a 35 larger scale; and Figs. 4, 5 and 6 cross sections on the corresponding section lines of Fig. 2 but on a larger scale.

Referring to the present embodiment of 40 my invention as herein shown, the drilling machine comprises three main parts, to-wit: the drill proper, the mounting therefor and the cone adjustable on the mounting. The drill proper, which is indicated at 1, 45 is here of the hand or portable type adapted to be removably secured or clamped upon the mounting in the manner hereinafter explained in detail.

The mounting comprises a frame consisting 50 of four longitudinal members, preferably tubes 2 which are spaced or arranged in pairs as indicated in the drawings. The ends of these tubes are secured together in suitable manner as by means of plates 3

and bolts or studs 4, the latter being anchored into the ends of the tubes by screwing thereinto and having bolts 5 at their outer ends, as shown in detail in Fig. 3. The usual feed screw 6 is arranged substantially central of this mounting frame and has its 60 bearings at opposite ends in the end plates 3.

The mounting also comprises two cross heads 7 slidable upon said mounting and adapted to carry the drill proper. As shown the rear cross head 7 has lateral portions 65 8-8 provided with openings through which pass the upper pair of tubes 2 with the result that the cross head has an efficient bearing to the extent of the entire circumference of these two tubes. This rear cross 70 head is also provided with a sleeve nut 9 having screw threaded connection with the feed screw 6. As shown in Fig. 6, this sleeve nut is removably held in a longitudinal bore in this cross head by a nut 30 screwing onto 75 the forward end of the sleeve nut, the head of the sleeve nut contacting the rear face of the cross head.

The cross head 7 is further provided with a rearwardly extending plate 10 to which 80 is adjustably secured a bracket or cradle 11 adapted to receive and hold the handle portion 12 of the drill. The bracket is adjustable on the plate 10 by reason of the provision of the bolt 13 screwing into plate and 85 the slot 14 therein, Fig. 6.

The front cross head 15 is provided with two lateral portions 16-16 provided with 90 openings to receive the two upper tubes 2 and to have bearing thereon as to their entire circumference as shown in Fig. 4. The two cross heads are secured together by means of the two longitudinal bolts 17-17 passing therethrough and provided at their ends with the nuts 18.

The cross head 15 is provided centrally and on its upper side with a curved saddle portion 19 adapted to receive the forward portion of the drill proper which is clamped thereto in the following manner:—The 100 curved clamping member 20 is pivoted at 21 to one side of the cross head 15 and at the upper end thereof as clearly shown in Fig. 4. The clamping member is of such conformation on its inner side as to fit the contour of the drill upon which it presses. The free end of this clamping member is provided with an outwardly extending lug 22

which is slotted from its outer end to receive the swinging clamping bolt 23 which is pivoted at 24 to the opposite upper end of the cross head 15. This bolt is provided with a 5 nut 25 for securing the same in place when the drill is clamped in position on the mounting.

The cone consists of a body portion 26 and four tubular extensions 27 arranged in 10 pairs with the members of each pair in axial alignment and adapted to receive and be slidable upon the lower pair of tubes 2. The cone is adjustable on these tubes, preferably by means of the slit tube 28 arranged 15 between two members of one pair of said extensions 27 and adapted to be clamped upon one of the tubes 2 by means of bolt 29.

There is thus provided a comparatively 20 simple but efficient mounting which is capable of elastic or weaving action which takes care of the strains and stresses without interfering with the practical operation of the drill and without resulting in any injury to or breakage of the mounting 25 or any other parts of the drilling machine.

Moreover I provide a simple and efficient cone structure so related to the mounting that it can be readily adjusted to any desired position with respect to such mounting. Although I prefer to use round, hollow rods for the skeleton frame, solid rods and rods of other than round form may be used.

I claim:

1. A drill mounting comprising a frame 35 consisting of two pairs of parallel rods connected together at their ends, and cross heads adapted to receive the drill proper and mounted on such frame.

2. A drill mounting comprising a frame 40 consisting of two pairs of parallel hollow rods connected together at their ends, and cross heads adapted to receive the drill proper and adjustably mounted on such frame.

45 3. A drill mounting comprising a frame consisting of pairs of rods connected together at their ends, cross heads slidably mounted on the upper pair of rods, and a supporting device mounted on the lower pair 50 of rods.

4. A drill mounting comprising a frame 55 consisting of pairs of rods, end plates for securing the ends of such rods together, a feed screw having bearings in such plates and arranged substantially centrally of such frame, and cross heads adapted to receive the drill proper and slidably mounted on such frame.

5. A drill mounting comprising a frame 60 65 consisting of two pairs of parallel rods connected together at their ends, a cross head adapted to receive the drill proper and having openings through which a pair of such rods pass whereby the cross head may slide on the frame and a feed screw located with-

in said frame and parallel to the rods and cooperating with the cross head.

6. A drill mounting comprising a frame 70 consisting of a plurality of rods connected together at their ends, a pair of cross heads connected together and adapted to receive the drill proper, said heads having openings through which a pair of such rods pass whereby the cross heads may slide on the frame and a feed screw located within said 75 frame and parallel to the rods and cooperating with the cross head.

7. A drill mounting comprising a frame 80 consisting of a plurality of rods connected together at their ends, and a pair of cross heads connected together and adapted to receive the drill proper, said heads having openings through which a pair of such rods pass whereby the cross heads may slide on the frame, and a feed screw supported in 85 such frame and adapted to engage one of the cross heads.

8. A drill mounting comprising a frame 90 consisting of two pairs of parallel rods connected together at their ends, and a pair of cross heads connected together and adapted to receive the drill proper, said heads having openings through which a pair of such rods pass whereby the cross heads may slide on the frame, one of the cross heads having 95 an adjustable cradle adapted to receive the handle end of the drill and a feed screw co-operating with the latter head and located in the interior of said frame.

9. A drill mounting comprising a frame 100 consisting of a plurality of rods connected together at their ends, and a pair of cross heads connected together and adapted to receive the drill proper, said heads having openings through which a pair of such rods 105 pass whereby the cross heads may slide on the frame, one of the cross heads having a saddle portion and a clamping member adapted to engage the drill proper and hold it anchored to the saddle and a feed screw 110 cooperating with the latter head and located in the interior of said frame.

10. A drill mounting comprising a frame 115 consisting of a plurality of rods connected together at their ends, and a pair of cross heads connected together and adapted to receive the drill proper, a feed screw located within said frame and cooperating with one of the heads, said heads having openings through which a pair of such rods pass 120 whereby the cross heads may slide on the frame, one of the cross heads having a saddle portion and a clamping member adapted to engage the drill proper and hold it anchored to the saddle, such member being pivoted to 125 one side of the cross head and a swinging bolt on the other side thereof to engage the free end of the clamping member.

11. A drill mounting comprising a frame 130 consisting of a plurality of pairs of rods

- connected together at their ends, cross heads mounted to slide on the other pair of such rods, and means for securing the cone in adjusted position thereon. 20
- 5 12. A drill mounting comprising a frame consisting of a plurality of pairs of rods connected together at their ends, cross heads slidably mounted on one pair of such rods, a cone having tubular extensions mounted on
- 10 the other pair of such rods, and means for securing the cone in adjusted position thereon.
13. A drill mounting comprising a frame consisting of a plurality of pairs of rods connected together at their ends, cross heads slidably mounted on one pair of such rods, a cone having two pairs of tubular extensions, the members of each pair being mounted to slide on the other pair of such rods, and means for securing the cone in adjusted position thereon, such means comprising 25 a clamping collar arranged between the members of one pair of such extensions and adapted to be clamped to the rod which passes through such particular extensions. 30
